UNITED STATES PATENT OFFICE.

FRANK H. PREBLE AND KELLUM D. GRANT, OF PHILADELPHIA, PENNSYLVANIA.

AUTOMATIC HEN-MARKER.

1,098,971.

Specification of Letters Patent.

Patented June 2, 1914.

Application filed February 3, 1914. Serial No. 816,192.

To all whom it may concern:

Be it known that we, FRANK H. PREBLE and KELLUM D. GRANT, citizens of the United States, and residents of Philadelphia, in the county of Philadelphia and State of Pennsylvania, have invented a new and Improved Automatic Hen-Marker, of which the following is a full, clear, and exact description.

10 This invention relates to the care of live stock, and has particular reference to poultry apparatus.

Among the objects of the invention is to provide a means for automatically classifying 15 hens as to their propensity to enter a nest.

Among the objects of our invention, more definitely stated, therefore, is to provide a nest construction with devices whereby, 20 when a hen enters the nest, a drop of ink or paint of any suitable nature will be caused to drop upon her back. By this means, therefore the hens which enter nests will be marked so as to clearly identify them and 25 distinguish them from the hens which do not frequent the nests.

The foregoing and other objects of the invention will hereinafter be more fully described and claimed and illustrated in the 30 drawings forming a part of this specification in which like characters of reference indicate corresponding parts in all the views, and in which—

Figure 1 is a front elevation of a preferred form of our invention, certain parts of the structure being in section, and the view indicating the nest in normal unoccupied position; Fig. 2 is a similar view indicating the parts assumed by them when the 40 nest is occupied by a single hen; Fig. 3 is a vertical transverse section on the line 3—3 of Fig. 1; Fig. 4 is a vertical section of the color applying mechanism, the parts being in the position indicated in Fig. 1; Fig. 5 is 45 a transverse section on the line 5—5 of Fig. 4, the top of the color casing being shown in plan view; Fig. 6 is a transverse section on the line 6—6 of Fig. 4; and Fig. 7 is a side elevation of a hen's nest made in accordance with this invention, with a modified means for supporting it.

The several parts of the device may be made of any suitable materials, and the relative sizes and proportions, as well as the 55 general design of the mechanism, may be varied to a considerable extent without de-

parting from the spirit of the invention hereinafter more fully set forth and specifically claimed.

Referring to the drawings for a more specific description of the invention, we show at 10 a nest suspended with its rear closed wall 11 in close proximity to a fixed wall 12 of a building. Said nest 10 is supported in position adjacent said wall but movable vertically along the same so as to respond to the weight of the hen or hens. Any suitable means may be provided to support the nest in elevated position in such a manner as to allow it to sink under the force of the 60 hen's weight for the purposes to be described below. One of the preferred supporting means comprises one or more counterweights connected by a flexible connection 13 such as a cord connected at one end 65 to a point 14 adjacent the top of the nest structure and at the other end at a point 15 to a counterweight 16. The intermediate portion of the cord 13 is guided over any suitable number or arrangement of direction 70 pulleys 17 arranged adjacent a bracket 18 secured above the nest to the wall 12. The weight of the counterweight 16 is sufficient 75 to elevate the nest when empty, the extent of movement of the nest and counterweight 80 being limited by stop means below the counterweight.

At 19 we show a casing secured in a clamp 20 extending from the bracket 18. Said casing is designed to hold any suitable 85 character of ink, paint or other marking material which will be referred to herein as color and indicated at C. We do not limit ourselves to the use of any particular character of color but employ any commodity of 90 a suitable nature in liquid form which may be dispensed from the casing in minute quantities with reliability and for a long period of time so as not to require constant attention by the operator. The casing is 95 maintained, as above premised, in a stationary position above the nest and preferably just above the spot or place occupied by the hen as she enters the nest and depresses it by her weight. At 21 is shown 100 a standard secured to or carried by the top of the casing and extending upwardly parallel to the vertical axis thereof. A lever 22 is connected by pin and slot connection 105 23 to said standard. The shorter end of the lever 22 co-operates normally with a frusto-conical collar 24 adjustably connected to a

central stem 25 adapted to reciprocate in said casing and through the top thereof. A valve 26 is carried by the lower end of said stem and cooperates with a discharge nipple 27 extending through the bottom of the casing. A spring 28 within the casing acts between the top thereof and said valve to maintain the valve closed and the stem in its normal depressed position, as shown in Fig. 4. The lever 22 is maintained normally in the position shown by means of a spring 29 connected at one end at a point 30, the other end of the spring being connected to the standard. The spring acts to force the lever toward the stem 25. The outer or longer end of the lever is maintained normally elevated by means of a spring 31 supported upon a lug 32 at its lower end. By adjusting the collar 24 up or down the stem, the extent of vertical movement thereof, and hence the amount of color to be discharged thereby at each reciprocation, may be varied and the adjustment may be made secured by one or more lock nuts 24^a. A cord 33 secured at its upper end to the outer end of the lever 22 and connected at its lower end at the point 34 to the hen's nest causes the weight of the hen added to the nest to actuate the lever 22 and lift the stem 25, allowing a drop or more of the color to enter the nipple from which it will be dropped or spurted by the action of the stem as it drops to its normal position after the shorter end of the lever snaps past the collar 24. When the hen leaves the nest the counterweight 16 will restore the nest to normal position, slackening the cord 33 and allowing the spring 31 to restore the shorter end or nose of the lever 22 beneath the collar 24, the slotted connection at 23 allowing the lever to move outwardly so as to wipe over the inclined surface of said collar. Should the nest which is occupied by one hen be entered by another, the latter hen will receive a mark of color from the same mechanism and in a manner substantially the same as above described in connection with the marking of the first hen, but for this purpose we provide an auxiliary lever 22' supported upon a shorter standard 21' and resisted by a shorter spring 31'. The cord 33' connected to the mechanism has normally sufficient slack to permit the operation of the nest due to the weight of the first hen only without actuating the lever 22'. In other words, the first hen depresses the nest to a distance proportional only to her own weight, lifting the counterweight 16 in so doing. The counterweight 16 in this form of the invention is limited in its upward movement by one or more bolts 35 having loose connection with an auxiliary counterweight 16'. Said counterweight 16', therefore, acts as a stop means to limit the movement of the nest when supporting a

single hen. The lever 22 and the parts associated therewith always respond to the presence of a single hen, and if such hen leaves the nest before another comes, the lever 22' will not be actuated. If, however, a second hen enters the nest, the nest will be further depressed due to the additional weight, the counterweight 16' being then picked up and the cord 33' will operate the lever 22' and the stem through contact with a collar 24' adjustable on the stem in the manner above described. The second hen, therefore, entering the nest will be marked as a layer. The counterweights are normally supported by brackets 36 secured to 80 the guide rails 37 along the wall 12.

In Fig. 7 we show a modification of construction in which the nest 10 is supported normally upon a plurality of springs 16^a and 16^b corresponding in function to the counterweights 16 and 16' respectively, said springs acting between an ear 38 connected to the end of the nest and a collar 39 secured to a bracket 40 along which the nest is guided during its vertical movements. A second ear 38' may be connected adjacent the bottom of the nest to steady and guide it along said bracket 40. The operation of the nest in this embodiment of the invention is the same as above set forth. The spring 16^a is sufficient to hold the nest in normal elevated position and is just weak enough to allow the nest to be depressed by a single hen, and when the nest is occupied by two hens both springs will be depressed, allowing the nest to sink to its next position.

Having thus described our invention, we claim as new and desire to secure by Letters Patent:—

1. In a device of the character set forth, the combination of a nest, means to support the nest for vertical movements responsive to the weight of a hen, and color applying means above the nest actuated by the weight of the hen as she enters the nest to cause a drop of color to be applied to her back automatically.

2. In a device of the character set forth, the combination of a nest, counterbalancing means serving to hold the nest normally elevated but subject to depression by the weight of a hen entering the nest, a casing above the nest adapted to contain color, and connections between the nest and the color holder serving to automatically discharge a drop of color upon the hen as she enters and depresses the nest.

3. In a device of the character set forth, the combination of a hen's nest, means to hold the nest normally elevated, said holding means being adapted to allow the nest to be depressed to a certain extent by the weight of one hen and to a further extent by the weight of a second hen therein, means above the nest to apply color to a hen enter-

ing the nest, and connections between said color means and the nest whereby the color means will be operated in succession by the several hens entering the nest.

- 5 4. In a device of the character set forth, the combination of a nest, means to hold the nest normally elevated but responsive to the weight of a hen entering the nest to lower the nest, a color casing supported 10 above the nest, valve mechanism within the casing including a stem extending through the top thereof, means connected to the color casing coöperating with said stem to reciprocate it, and a connection between the casing 15 and the reciprocating means to cause a modicum of color to be deposited upon the hen as she enters and depresses the nest.
5. The herein described hen marker com-

prising a nest, means normally supporting 20 the nest in elevated position subject to depression by hens entering the same, in succession, a color casing above the nest, said casing including a valve having a stem reciprocating therein, a plurality of collars 25 connected to said stem, and means adapted to act on said collars successively to deposit a modicum of color upon each hen entering the nest.

In testimony whereof we have signed our 30 names to this specification in the presence of two subscribing witnesses.
